CLAIM

The ornamental design for a car seat cover for baby, as shown and described.

DESCRIPTION

FIG. 1 is a front perspective view of a car seat cover for baby, showing my new design in a first position of use;

FIG. 2 is another front perspective view of a car seat cover for baby, shown in a second position of use;

FIG. 3 is a front elevational view of the car seat cover for baby, shown in the first position of use;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

(Continued)

The broken lines in the drawings illustrate the portions of the car seat cover for baby, which form no part of the claimed design.
